FLUSH TANK ASSEMBLY

Roland W. Downin, Port Deposit, Md., assignor to
Valguard Company, Inc., Port Deposit, Md., a corpora-
tion of Maryland

Filed Feb. 29, 1960, Ser. No. 11,880

17 Claims. (Cl. 4—41)

This invention relates to a novel assembly for flush tanks of the type in general use as a bathroom fixture. Apparatus of this type have been more or less "frozen" as to design for many years in a general combination comprising an inlet pipe for valve, a float on a lever arm which opens and closes the inlet valve in a gradual manner, an overflow pipe to prevent overrunning of the flush tank, a flush valve which seats on a bottom outlet under pressure of the water head in the tank, and a hand lever connecting with the flush valve to lift it and thus break the water head pressure on it to permit it to float freely until the tank has been emptied, followed by the re-seating of the flush valve in closing relation and refilling of the tank due to dropping of the inlet valve controlling float.

Although in standard use over a long period, this flush tank arrangement has nevertheless been attended with many shortcomings with much in the way of improvement left to be desired. For example, in the conventional system, the parts are numerous and consist wholly of metal. As a result, early corrosion is common, leading to leaks and malfunctioning, as well as a short life for the system. In addition, the assembly is complex and delicate in its settings, often proving too formidable for the home repairman, and therefore requiring the services of a plumber in emergencies. For example, a common complaint as to existing systems has to do with the upright wire stem on the flush valve ball, which has a sliding connection with the manual lever and operates in an eyelet guide. This element is extremely sensitive in adjustment and frequently jams on the up-stroke, the down-stroke, or both. To complicate the problem, the average householder is usually at a loss to know just what must be done to restore normal operation. This malfunctioning is even more serious when the degree of maladjustment is small since this may be undetected with a serious waste of water resulting.

In addition, the existing inlet valve arrangements are faulty in that they involve repeated closure of the seat by the same surfaces, leading to early leakage, this being aggravated by the fact that the seating is a gradual process.

By the system of the present invention I have contrived to overcome the foregoing recited defects by providing an assembly in which the parts are non-corrosive, few in number and easy of installation and removal, and in which the need for periodic adjustment has been eliminated. In addition, my novel system has provided consistent functioning for the flush valve float, and besides improving the general functioning of the inlet valve, has at one and the same time introduced a snap action to this valve and positively removed the threat of water waste by removing the complete dependence of the inlet valve on the inlet control float.

It is therefore among the objects of the present invention to provide a flush tank system in which corrosion and water waste are eliminated, and malfunctioning minimized. Other objects are to provide a system which is simple in structure and design, few in parts, easy of installation and removal, and certain in operation.

These and other objects which will be readily apparent, not only to those skilled in the pertinent art, but to the general public as well, are attained by the present invention, a preferred embodiment of which is described

2

in the accompanying specification, and illustrated in the drawings, in which:

FIGURE 1 is a front elevational view of a flush tank, broken away, in part, to show the interior mechanism;

FIGURE 2 is a sectional view taken on the line 2—2 of FIGURE 1;

FIGURE 3 is an enlarged sectional view of a detail taken on the line 3—3 of FIGURE 1;

FIGURE 4 is a sectional view taken on the line 4—4 of FIGURE 3;

FIGURE 5 is an enlarged front elevational view of the flush valve float and its guide cage of FIGURE 2;

FIGURE 6 is a top plan view of FIGURE 5;

FIGURE 7 is an enlarged, sectional view of a detail along the line 7—7 of FIGURE 2;

FIGURE 8 is an enlarged, sectional view of a detail along the line 8—8 of FIGURE 1;

FIGURE 9 is a sectional view taken on the line 9—9 of FIGURE 5;

FIGURE 10 is an enlarged, exploded, top plan view of the split clamp ring;

FIGURE 11 is a front elevational view of the ring of FIGURE 10; and

FIGURE 12 is a side elevational view of the ring of FIGURE 10.

25 Referring to the drawings by characters of reference, in which like numbers refer to like parts throughout, there is shown, in FIGURE 1, a conventional flush tank 12 preferably of ceramic material with porcelain coating, and a removable top cover 14, with openings for the inlet pipe and the outlet pipe in the usual locations in the bottom. Thus, the opening for the inlet pipe is in the left rear corner of the tank, and the inlet pipe 16 of flexible tubing such as copper, plastic or the like is anchored in the fitting 18 at the opening, and is secured by exterior fitting 20, acting as a clamping nut. The flexible inlet pipe 16 is bent in an arc in order to locate the supply valve centrally of the tank for its novel mode of actuation by the float lever arm. It is a further consequence of this arrangement that the supply valve is in close proximity to the overflow pipe. The supply valve, indicated generally by the numeral 22, and later to be described in detail, carries an elbow 24 through which it is attached to the end of inlet pipe 16 by the usual clamp nut 26 in a manner to hang downwardly, and threadedly carries at its lower end a feed pipe 28 leading to a point near the bottom of the tank, for quiet and splashless filling, according to the usual practice in the art.

As best seen in FIGURE 9, the overflow pipe 30 and the outflow valve seat unit 32 are integral parts of a single casting, which is preferably of brass. The valve seat unit is a pipe of relatively large diameter occupying the central opening in the bottom of the flush tank, and having an interior, stop flange 34 engaging a gasket washer 36, and having a threaded, lower end receiving a lock nut 38 and washer 40 exteriorly of the flush tank.

Outflow through the pipe 32 is controlled by a valve 42 in the form of a hollow sphere of rubber or the like material. The actual seat for the ball is provided in a replaceable, plastic ring insert 44 having a slanting inner wall, and which may be snapped in place by means of a slight external bead 46 received in an annular recess in the inner wall of pipe 32, or held by any other suitable means. The importance of this feature is considerable, since damage to the valve seat, through corrosion, or as by dropping tools, for instance, is common, and results in serious leakage. Heretofore this has required replacement of the entire metal unit, including the overflow pipe.

The overflow pipe 30 rises vertically from a lateral extension 48 on pipe 32, the said extension being hollow so as to discharge water in the overflow pipe to the outlet pipe. Overflow pipe 30 has a rectangular opening 50

receiving an integral, protruding lug 52 on the supply valve 22 by which means the latter is anchored in place, when the lug is secured, as by a cotter pin 54. In the region of the hole 50 a substantial portion of the upper end of overflow pipe 30 is cut away to provide clearance for the diversion pipe 56 carried by the lower end of supply valve 22 and delivering into the overflow pipe, the purpose of which is to prevent back-feeding into the supply system.

The flush ball valve 42, which has a thickened bottom 58, or is otherwise weighted to prevent its turning over when not seated, has an upper lug 60 through which it is suspended from a chain 62. For lifting the ball off its seat to discharge the contents of the tank, chain 62 is anchored on a cross arm 64 secured to the inner arm 66 of the usual hand lever system having an exterior handle 68 and bushed in a fitting 70 on the tank.

Lifting of ball 42 from its seat removes the pressure on the ball, which is therupon urged upward by its buoyancy. Since the ball must automatically return to its seat after discharge of the water in the tank, its vertical motion must be guided. This is accomplished by means of a cylindrical cage indicated generally by the numeral 72. The cage, which is fabricated in one piece of soft, pliable plastic, as by injection molding, has a split form, as best seen in FIGURE 6, whereby it may be spread so as to be mounted in place or removed without necessity for removing any other part. The cage, composed, on its side, of a series of vertical panels 74 and a central horizontal band 76 has a horizontal top flange 78 and a horizontal bottom flange 80. Again referring to FIGURE 6, it will be seen that the end flanges 78, 80 and the central band 76 of the cage terminate short of semi-circular form, and are joined by strap sections 82 functioning as hinges, by means of which the cage may be spread to the form shown in broken lines, or assume a circular form surrounding the overflow pipe 30 when the cage is closed. Preferably the cage will have the open form in its normal, unstressed position, as molded. Flexible tongues 84 on strap hinges 82 serve to center them about the overflow pipe, and also to permit adaption to various sizes of pipes while avoiding looseness of fit. The cage is secured against upward vertical movement by means of a series of tongues 86 extending downwardly from the lower flange 80 and radially inward, and engaging beneath a shouldered portion 88 at the top of pipe 32.

After the open cage has been slipped down behind the overflow pipe 30 it is wrapped around this pipe and the main overflow pipe 32 with the tongues 86 engaging beneath the shoulder 88 of pipe 32, and the split flanges are brought into contact along the line 90 (FIGURES 2 and 6). Thus mounted, the cage is secured in place by a pair of straps 92 with perforations by which they are forced into frictional engagement with small, headed knobs 94 formed on the outer sides of those vertical panels 74 of the cage defining the parting line. The cage is further secured on the top flanges 78 by means of a pair of plastic washers 96, force fitted over heads 98 formed by the mating of hemispherical components on the respective ends of the flange forming the parting line 90. As seen in FIGURE 7 the end flanges are provided with integral dowels 97. All of these fastening means are easily applied and easily removable, even after repeated use.

The main float system, controlling the supply valve, is mounted on and carried entirely by the supply valve. The latter, as seen in FIGURE 3, consists of a housing 100 with a central bore 102 having an internal, annular, transverse flange 104 bevelled to form a seat for ball 106. Journalled to the walls of housing 100 is a plastic shaft 108 having an eccentric 110 adapted to contact and lift ball 106 on rotation of the said shaft. Exterioly of valve housing 100, the shaft 108 has an integral, cup-shaped head, or knob 112, which supports a float lever arm 114 in keyed relation, whereby tilting of the arm

turns the shaft 108 to raise ball valve 106 through eccentric or cam 110. Coupling of the arm 114 to knob 112 is accomplished through a splined connection which communicates a turning torque to the valve shaft and which is slanted with respect to the turning axis (i.e. frustoconical); to prevent separation of the parts. Thus, the splined side wall 116 of the cavity in knob 112 is greater in diameter at the bottom of the cavity than at its rim, and this wall receives, in snugly mating relationship, the complementary, splined outer ends of a two piece clamping ring 118 in which the float lever 114 is supported. The split ring, which is shown in detail in FIGURES 10 to 12, is composed of identical half sections, each having a semi-cylindrical central portion 120 which engages the tubular float lever 114, a semi-cylindrical end shank 122 with circular ribs 124 and a half-tube 126, having at its outer end a series of splines 128 extending over a portion only of the outer face of the half tube to facilitate entry into the cavity of the valve knob 112. Splines 128 have, of course, a conical slant complementary to the splines in knob 112.

Coupling of the float lever arm to the supply valve is accomplished by bringing the clamp halves together around the lever arm, inserting the splined end into the valve knob and applying a metallic, looped keeper 130 between the ribs 124 on the outer shank parts 122. This manner of application is enabled by properly dimensioning the central band of the split clamp so that its inner diameter when the two halves are in full contact is less than the outer diameter of the lever tube 114, and the components on the splined end, when in contact clear the outer opening in knob 112 for ready insertion. Such clearance is also aided by the absence of splines in the regions adjacent the contact line of the tube halves. With the splines in place in the cavity of knob 112 the outer shank halves 122 are pressed into contact, so that the tube halves 126 separate, bringing the splines into mating engagement and thus locking the clamp to the knob 112, and the connection is secured by snapping the keeper 130 over the ribs 124. As in the case of the cage, the process is readily reversible for disassembly. Assembly of the clamp elements is further facilitated by providing on the two contact surfaces of each half of the splined tube of the clamp ring an integral dowel 132 and a dowel-receiving cavity 134.

For a main float, in lieu of the usual hollow, metal spheroid which is subject to corrosion and leakage, I have provided, on the end of the valve lever arm 114, a rectangular solid 136 of suitable low density foam plastic. This is attached to the outer end of the rocker arm 114 by a brass screw or bolt 138 engaging a threaded, solid, plastic insert 140 in the float.

In a very important aspect of my invention, there is provided within rocker tube 114 a freely rolling metal ball 142 retained in the tube by screw 138 at one end of the tube and by a plastic pin 144 at the other end. Pin 144 and screw 138 each have a surrounding rubber sleeve 146 to absorb the shock of the rolling ball in order to obviate noise and wear. It will be seen that after the float 136 has raised the rocker tube to a position slightly beyond the horizontal, the ball 142 will roll to the inner end of the tube, thus imparting to the valve shaft 108 and cam 110 a relatively quick final movement which permits the valve ball 106 to seat with rapidity and consequently with certainty. The rocker tube comes to rest upon contact with the terminal, transverse arm 64 of the hand-actuated lever, and in this position the supply valve control is removed from dependence upon the float 136 and no opening of the supply valve is possible until the weight of the ball has been overcome by operation of outer handle 68 which causes arm 64 to raise the inner end of tube 114. This action lifts ball 42 through chain 62 to empty the tank and also raises the rocker tube to a point where the ball 142 rolls to the outer end of the tube permitting the float 136 to follow the level of the

water downward lifting the ball 106 in the supply valve from its seat to refill the tank.

From the foregoing description it will be evident that I have provided a novel flush tank system which includes among its advantages all of those enumerated as among the objects sought, and in other recitals above. In addition, the ball feature in the supply valve provides an anti-syphon function in that it will, upon occurrence of any back-suction into the supply system, promptly seat at the top of the valve chamber to block back flow of water. Another feature is that the system is operable at any available pressure by simple adjustment of the splined connection to the proper angle. The ball feature in the supply valve avoids repeated seating of the same surfaces and thus brings about long life and certainty of operation.

In a generalization of advantages of my system, there are no washers, packing or troublesome linkages, the parts are corrosion-proof, the arrangement is simple, rugged, trouble free, fast, leak proof, silent, and saving of water, doubly vigilant in the matter of anti-syphoning, and operable at any supply pressure. No sensitive adjustments are involved, and no special tools are necessary.

While a certain preferred embodiment has been shown and described, the invention is not to be deemed as limited thereby, since various modifications and equivalents will be readily apparent to those skilled in the pertinent art, in the light of this disclosure, and the invention should not, therefore, be deemed as limited except insofar as shall appear from the spirit and scope of the appended claims.

I claim:

1. In a flush tank system having an outlet pipe with upstanding overflow pipe, an inlet supply fitting and a manually operable lever; a supply pipe leading from said fitting to said overflow pipe, a supply valve carried by said supply pipe, anchored to said overflow pipe and having a drip pipe leading into said overflow pipe, and a downwardly extending supply tube, check means in said valve comprising a ball and a seat therefor, a shaft in the supply valve including a cam arranged to unseat said ball, a rocker tube enclosing a freely rolling weight means and having an angularly adjustable, splined connection with said shaft, a low density, solid float carried on one end of said tube, a split, plastic cage removably anchored to, and secured in surrounding relation to said outlet pipe, a tubular plastic insert in said outlet pipe forming a valve seat, a hollow ball weighted on its lower side contained within said cage for vertical movement to and from said valve seat insert, a chain secured at one end of said hollow ball, and a lateral arm on the inner end of said manually operable lever to which the other end of said chain is attached, said lateral arm lying in the path of movement of the end of said rocker tube opposite said solid float, whereby to limit rocking of said tube on cutting off of the water supply and to lift said tube to resume water supply simultaneously with lifting of said hollow ball from its seat.

2. In a flush tank system having an outlet pipe with a ball valve seat and an upstanding overflow pipe, an inlet supply fitting and a manually operable lever; a supply pipe leading from said fitting to said overflow pipe, a supply valve carried by said supply pipe and anchored to said overflow pipe, check means in said valve comprising a ball and a seat therefor, a shaft in the supply valve including a cam arranged to unseat said ball, a rocker tube enclosing a freely rolling weight means and having an angularly adjustable, splined connection with said shaft, a low-density, solid float carried on one end of said tube, a split, plastic cage removably anchored to, and secured in surrounding relation to said outlet pipe, a hollow ball weighted on its lower side contained within said cage for vertical movement to and from said outlet pipe valve seat, a chain secured at one end to said hollow ball, and a lateral arm on the inner end of said

manually operable lever to which the other end of said chain is attached, said lateral arm lying in the path of movement of the end of said rocker tube opposite said solid float whereby to limit rocking of said tube on cutting off of the water supply, and to lift said tube to resume water supply simultaneously with lifting of said hollow ball from its seat.

3. In a flush tank system having an outlet pipe with a ball valve seat and an upstanding overflow pipe, an inlet supply fitting and a manually operable lever; a supply pipe leading from said fitting to said overflow pipe, a supply valve carried by said supply pipe adjacent said overflow pipe, check means in said valve comprising a ball and a seat therefor, a shaft in the supply valve including a cam arranged to unseat said ball, a hollow rocker arm enclosing a freely rolling weight means and having an angularly adjustable splined connection with said shaft, a float carried on one end of said rocker arm, a split, plastic cage removably anchored to and secured in surrounding relation to said outlet pipe, a hollow ball weighted on its lower side contained within said cage for vertical movement to and from said outlet pipe valve seat, a chain secured at one end to said hollow ball, and a lateral arm on the inner end of said manually operable lever to which the other end of said chain is attached, said lateral arm lying in the path of movement of the end of said rocker arm opposite said float whereby to limit movement of said rocker arm on cutting off of the water supply, and to lift said rocker arm to resume water supply simultaneously with lifting of said hollow ball from its seat.

4. In a flush tank system having an outlet pipe with a ball valve seat and an upstanding overflow pipe, an inlet supply fitting and a manually operable lever; a supply pipe leading from said fitting to said overflow pipe, a supply valve carried by said supply pipe adjacent said overflow pipe, check means in said valve comprising a ball and a seat therefor, a shaft in the supply valve including a cam arranged to unseat said ball, a hollow, rocker arm enclosing a freely rolling weight means and having a splined connection with said shaft, a float carried on one end of said rocker arm, a cage anchored to said outlet pipe in surrounding relation thereto, a hollow ball contained within said cage for vertical movement to and from said outlet pipe valve seat, a chain secured at one end of said hollow ball, and a lateral arm on the inner end of said manually operable lever to which the other end of said chain is attached, said lateral arm lying in the path of movement of the end of said rocker arm opposite said float whereby to limit movement of said rocker arm on cutting off of the water supply, and to lift said rocker arm to resume water supply simultaneously with lifting of said hollow ball from its seat.

5. In a flush tank system having an outlet pipe with a ball valve seat and an upstanding overflow pipe, an inlet supply fitting and a manually operable lever; a supply pipe leading from said fitting to said overflow pipe, a supply valve carried by said supply pipe, check means in said valve comprising a ball and a seat therefor, a shaft in the supply valve including a cam arranged to unseat said ball, a hollow, rocker arm enclosing a freely rolling weight means and medially connected to said shaft, a float carried on one end of said rocker arm, a cage surrounding said outlet pipe, a spherical float contained within said cage, and a flexible lifting member attached to said spherical float and to said manually operable lever.

6. In a flush tank system having an outlet pipe with a ball valve seat, an upstanding overflow pipe and a manually operable lever, a supply valve anchored to said overflow pipe, check means in said valve comprising a ball and a seat therefor, a shaft in the supply valve including a cam arranged to unseat said ball, a hollow, rocker arm enclosing a freely rolling weight means and medially connected to said shaft to rotate the shaft on

rocking, a float carried on one end of said rocker arm, a cage surrounding said outlet pipe, a spherical float contained within said cage, and a flexible lifting member attached to said spherical float and to said manually operable lever.

7. In combination, a supply valve having check means comprising a ball and seat, a shaft in said valve having a cam adapted to unseat said ball, an external knob on said shaft having a circular cavity in its outer face with a frusto-conical splined side wall of inwardly increasing diameter, a rocker tube enclosing a freely rolling weight of spherical form, a float on one end of said tube, a two-part ring clamp surrounding said rocker tube, a tubular extension on one side of said clamp with its outer end splined in part in a sense complementary to the splines of said knob and mating with said latter splines, an extension on the other side of said ring clamp, and a keeper on said latter extension holding the parts thereof in contact, the parts of said tubular extension being separate when said keeper is in place and said splines in mutually nested relation.

8. In combination, a supply valve having check means comprising a ball and seat, a shaft in said valve having a cam adapted to unseat said ball, an external knob on said shaft having splines, a rocker tube enclosing a freely rolling weight means, a float on one end of said tube, a two-part ring clamp surrounding said rocker tube medially thereof, an extension on the clamp on one side of said tube having splines mated with the splines of said knob, an extension on the end of said clamp on the other side of said tube, and keeper means holding the parts of said extension together on the said other side of said tube.

9. In combination, a supply valve having check means comprising a ball and seat, a shaft in said valve having a cam adapted to unseat said ball, a rocker tube enclosing a freely rolling weight means, a float on one end of said tube, and means attached to said shaft and to said tube medially thereof whereby rocking of said tube rotates said shaft.

10. A supply valve comprising a housing having a through passage, means in said passage providing a valve seat, a ball valve mating with said seat, a shaft journaled laterally of said passage, a cam on said shaft arranged to unseat said ball, and a turning knob on said shaft for connection to a float rocker arm, said knob having a frusto-conical recess in its outer face of increasing diameter inwardly of the knob, and splines in its slanting wall.

11. In combination, a clamp and cam shaft coupling comprising a two part ring clamp divided along a diameter, matching lugs extending from the opposite side of said ring and having a frusto-conical outer portion of outwardly increasing radius with opposite segments splined, and a cam shaft having at one end a turning knob with a frusto-conical recess in its outer face having splines in mating relation to the splines of the ring clamp.

12. A coupling comprising a two part ring clamp divided along a diameter, matching lugs extending from the parts on each side of the ring, the matching parts on one side comprising a head with a frusto-conical periphery of outwardly increasing diameter and splined to a limited

extent on each of the respective parts, and a connecting knob having a recessed face with frusto-conical side wall splined in a manner to mate with the splines on said head.

5 13. A ring clamp and connector comprising a two part ring band divided along a diameter, and matching lugs extending from the parts on each side of the band, the matching parts on one side comprising a head with a frusto-conical periphery of outwardly increasing diameter and splined along limited segments on opposite sides of the dividing line.

10 14. An attachment for use in a flush tank system having an outlet pipe and upstanding overflow pipe, including a cage comprising a pair of semi-cylindrical sections of open-work structure with inner diameter in excess of that of the outlet pipe, a series of flexible bands joining said sections and adapted to operate as a hinge and assume a cylindrical form surrounding the overflow pipe when the said pair of sections are brought into conjunction, as when surrounding the outlet pipe, headed elements on the sides of the cage parts, flexible straps with perforations for joining the parts of said cage by snap fit over said elements, headed elements on the top of said cage at the line of parting, and snap-fastener washers to engage said latter elements.

15 15. An attachment for use in a flush tank system having an outlet pipe and upstanding overflow pipe, including a cage for confining the float ball valve of said outlet pipe comprising a pair of semi-cylindrical sections of open-work structure with inner diameter in excess of an outlet pipe, a series of flexible bands joining said sections and adapted to operate as a hinge and assume a cylindrical form surrounding the overflow pipe when the said pair of sections are brought into conjunction, as when surrounding the outlet pipe, and means to secure said cage in closed position of the parts.

20 16. In a cage as in claim 14, downwardly and inwardly extending fingers on the lower edges of said sections.

25 17. An improved guide sleeve construction for a flush tank of the type having a ball valve arranged for upward valve-opening movement along the long axis of the sleeve from a valve-closed position wherein the ball is seated on a flushing outlet opening at the bottom of the sleeve, comprising: A perforate sleeve divided along its long axis into at least two segments, each extending circumferentially part way around the long axis of the sleeve; means for mounting said sleeve on said tank to extend over said bottom outlet and vertically upward therefrom for valve-guiding purposes; and means for removably connecting the segments of said sleeve together to provide, when the sleeve is mounted, for the ready separation of at least one of its segments from another for valve access purposes.
